Inventor,
Stephen Scotton

United States Patent Office.

STEPHEN SCOTTON, OF RICHMOND, INDIANA.

Letters Patent No. 90,398, dated May 25, 1869.

IMPROVEMENT IN TREE-BOXES.

The Schedule referred to in these Letters Patent and making part of the same.

To all whom it may concern:

Be it known that I, STEPHEN SCOTTON, of Richmond, Wayne county, and State of Indiana, have made new and useful Improvements in "Tree-Boxes;" and I hereby declare the following to be a full and exact description of the same, reference being had to the drawings that accompany and form a part of these specifications.

The object of my invention is to provide a box or device for the protection and support of young trees, designed not only to secure them from damage by horses or cattle, but also to keep them upright, and prevent their being swayed about or broken by the wind.

Figure 1, perspective view.

Figure 2 shows one form of joint or fastening where the two ends of the iron rod, or ring A, that passes through the upright slats B B, come together, and is passed through slot B at C, both ends of said iron rod having been pointed. One end is turned up, and inclined in the slot, and the other end is turned down, and clinched into the other side of the slot, as shown at C in fig. 2, and partially shown at C in fig. 1.

Figure 3 shows another mode of fastening the iron rod A. A lap joint is made by bevelling off the meeting faces of the rod, so that when lapped together the rod is of the same size there as in other places, and can be forced into the same sized hole as the rod passes through in other places. The two meeting faces in this joint are intended to be notched, or ruffed, like the

face of a file, so that when forced into a hole somewhat smaller than the rod, they will adhere firmly together, and not be easily drawn apart.

Figure 4 shows still another and more simple plan of uniting the meeting ends of the rod A, in this case the two ends merely butting together, as shown at D in figs. 1 and 4. This way may answer better where wide slats are used.

As a great variety of forms and styles of wooden slats will be used, some wide and flat, some square, and others round, some one of these joints is calculated to answer for all the different styles and patterns.

One leading feature of this invention consists in making the holes in the slats B B a little smaller than the iron rod A, and then, by forcing the rod through the holes, a great degree of firmness and solidity is given to the finished tree-box. Also, by wetting the joints or joint-holes with salt water, a rust is produced that tends greatly to cause them to adhere more firmly together.

What I claim as my invention, and desire to secure by Letters Patent, is—

The combination of the slats B B with the iron rod A, formed and secured substantially as described, and for the purposes herein set forth.

STEPHEN SCOTTON.
